UNITED STATES PATENT OFFICE.

WALTER LAMBERT, OF YAKIMA, WASHINGTON.

DIGGER.

1,360,120.

Specification of Letters Patent. Patented Nov. 23, 1920.

Application filed July 25, 1919. Serial No. 313,162.

To all whom it may concern:

Be it known that I, WALTER LAMBERT, a citizen of the United States, and a resident of Yakima, in the county of Yakima and State of Washington, have invented a new and Improved Digger, of which the following is a full, clear, and exact description.

The present invention relates to new and useful improvements in diggers, and it pertains more particularly to devices of this character especially adapted for digging holes for fence posts, plants, etc.

Reference is had to the accompanying drawings forming a part of this specification, in which like characters of reference indicate corresponding parts in all the views, and in which—

Figure 1 is a view in elevation of the digger;

Fig. 2 is a sectional view taken on the line 2—2 of Fig. 1;

Fig. 3 is a sectional view taken on the line 3—3 of Fig. 1;

Fig. 4 is a detail vertical sectional view taken at right angles to Fig. 3, on the line 4—4 of Fig. 3.

Referring more particularly to the drawings, the reference character 5 designates a handle, and rigidly secured to the lower end 30 of said handle 5, is a casting 6. This casting 6 is provided with a tang 7, which projects upwardly into the handle 5, as shown in Fig. 3. The casting 6 is provided with a flange 8, and depending from the flange 8 is a lug 9, which lug is perforated at 10.

Pivotedly secured to the depending lug 9, by means of a pin 12, are digging blades 11, and each of said blades is provided on its upper end with spaced lugs 13, between each 40 pair of which is pivotally mounted a link 14.

The upper end of each of these links 14 is pivotally connected as at 15, to a collar 16, and said collar 16 is rigidly secured to the lower end of a sliding sleeve 17, by means

of rivets or the like 18. The sleeve 17 is 45 provided near its lower end with diametrically opposite slots 17' and passing through the handle 5 and the tang 7, is a pin 16', the length of said pin being equal to the diameter of the sleeve and handle 5.

Interposed between the lower end of the sliding sleeve 17 and the casting 6, is a coil spring 19, the tension of which serves to maintain the digging blades 11 in extended position, in which position they are shown 55 in the drawings.

The operation of the device is as follows:

With the parts in the position shown in the drawings, the blades 11 are forced into the ground by means of the handle 5. The 60 sliding sleeve 17 is now moved longitudinally of the handle, and through the medium of the links 14, the blades 11 are closed, at the same time compressing the coil spring 19. With the jaws in the closed position, 65 they are lifted from the hole, after which the sleeve is released and moved longitudinally of the handle 5, to open the jaws 11 and dump the dirt therein contained.

Having thus described the invention, what 70 is claimed is:

A digger comprising a handle, a casting rigidly carried by one end of said handle, a plurality of digging blades pivotally carried by said casting, a sleeve slidably mounted on 75 said handle and provided with diametrically opposed elongated slots, a pin extending transversely of said handle and having its ends operating in said elongated slots, a plurality of links carried by said sliding sleeve 80 and pivotally connected to said digging blades, and a spring interposed between the free end of the sliding sleeve and the casting carried by the handle whereby the digging elements are normally maintained in 85 parallel relation one with the other.

WALTER LAMBERT.
